UNITED STATES PATENT OFFICE.

ERNEST FRANK HANSON, OF DORCHESTER, MASSACHUSETTS, ASSIGNOR TO
LIBRARY BUREAU, OF BOSTON, MASSACHUSETTS, A CORPORATION OF
MASSACHUSETTS.

NUMBERING ATTACHMENT FOR PRINTING-PRESSES.

SPECIFICATION forming part of Letters Patent No. 692,515, dated February 4, 1902.

Application filed March 7, 1901. Serial No. 50,170. (No model.)

To all whom it may concern:

Be it known that I, ERNEST FRANK HANSON, a citizen of the United States, residing at Dorchester, in the county of Suffolk and State of Massachusetts, have invented a new and useful Improvement in Numbering Attachments for Printing-PresSES, of which the following is a specification.

My invention consists of a number-printing mechanism whereby a succession of printed blanks may be consecutively numbered while being printed with other characters or not, as desired.

My number-printing machine involves the use of a type-disk counter or progressive-numbering device in which the arrangement and mode of progressive advance of the disks may be according to any acceptable plan. This number-printing device is mounted upon or in one of the two essential and prime members of the press, which are exemplified by the platens and printing-cylinders in common use, and is actuated in harmony with the recurrent cycle of movement of the printing-press, so that at each printing impact of the number-printer the numbering-disks have advanced one unit and the number printed advances correspondingly in the series.

In the drawings hereto annexed, wherein I use like letters to denote like parts, an embodiment of my invention is illustrated.

Figure 1 shows in vertical cross-section the cylinders of a rotary printing-press and the arrangement of my number-printing device thereon. Fig. 2 shows in elevation the press-cylinders and number-printing device. Fig. 3 shows in vertical cross-section the details of the numbering mechanism. Fig. 4 shows the same in vertical longitudinal section; and Fig. 5 shows the numbering devices in cross-section, as in Fig. 1, but in a different position.

Figs. 1 and 2 show in a general way the application of my invention to a cylinder-press. C and C' are the two prime members of the press—in this case the press-cylinders—rotating in the direction indicated by the arrows. T is the so-called "turtle," which is ordinarily used for the reception of type, secured to the cylinder C by screws F. The

number-printing device P is mounted in the turtle T by means of the filling-blocks F. The printing devices are actuated in harmony with the movement of the press by means of a wiper W, of which w' is a wiper-roll secured to a short shaft w², which is journaled in the fork of the arm w³, which arm is secured at the proper position on the bar w⁴ by a set-screw w⁵. The bar w⁴ is rigidly secured to the press-frame. As the press-cylinder C rotates after each printing impact of the numbering-disks the disk-advancing mechanism is actuated by the wiper W, between which and the number-printing devices there is the relative movement required to produce this effect.

In Figs. 3, 4, and 5 there are shown the details of a number-printing mechanism which embodies my invention or substantial and material parts thereof. The case B is a rectangular box, preferably of metal, either cast solid or made of securely-fastened plates. The frame F fits within the case B with a sliding fit and is supported on or secured to (or both) the case B by the springs S, which fit within the sockets S of the frame F. These springs are sufficiently stiff to offer substantial resistance to the printing impact, but yield to the influence of the counter-actuator, presently to be described. The upright arm F² of the frame F is provided with a protruding cam F', which performs the functions of a disk-advancer, as it is that portion of the counter mechanism by which the progressive advance of the numbering-disks is brought about. Upon the shaft d, which extends the length of the frame F, the disks D' d² d³ Dⁿ are hung. These disks carry the number-types and are provided with the ratchets d' and d², wherewith to be advanced progressively in the usual manner. Upon the outside of the frame-arm F² there projects the pivot-pin g', which serves as a pivot-bearing for the rocker-lever G. The lever G has a heel g³ and a toe g⁴, and the pin g⁴ is secured to the toe g³ and projects through the curved slot f², which is cut for the purpose in the arm F². Mounted on the shaft d on the side of the frame-arm F² there is hung the bell-crank lever L. This lever has a forked end l', which engages with

the pin g^4 , and a pawl-shaft end L^2 , which actuates the pawl-shaft i and the pawls i^1 i^2 . The pawl i^1 engages with the teeth of the ratchet-wheel d' and advances the first disk 5 D' of the series with each throw of the pawl i^1 . The spring i^3 serves by its torsional effect to hold the pawls in effective position. The lever-arm L' , mounted on the disk-shaft d , constitutes a proper support for the farther 10 end of the pawl-shaft i .

The counter-actuator, consisting of the wiper W , Figs. 1 and 2, is partially shown in Figs. 3, 4, and 5. The wiper-roll w' on its shaft w^2 is so mounted in the press that the 15 relative movement of the parts carries the wiper-roll w' in a path substantially parallel to the face of the printing-press member, platen, or cylinder or what is the same thing, so that the movement, say, of the cylinder 20 carries the printing-counter in a path which is intersected by the wiper-roll. The movement of the wiper-roll relatively to the printing-counter is indicated by the arrows in Figs. 3 and 5. The heel g^2 of the rocker G projects into an opening b , cut for the purpose 25 in the side of the case B , and stands between the ledges b' and b^2 , as shown in Figs. 3 and 5. The high part of the cam F' projects above 30 the top of the case B , but lies below the printing-surface, (the plane of the top row of disk-types,) so that the cam F' does not in any way interfere with the act of printing and does not come in contact with the inking-rolls wherever 35 they may be placed or however they may be operated. As the press, with the printing-counter secured in the face of one of the prime members of the press, proceeds to print it brings the disk-advancer of the counter into operative relationship with the counter-actuator. 40 In the illustration here given the rotation of the cylinder C brings the cam F' of the counter P into contact with the stationary wiper-roll w' after each printing impact. The parts are shown at the moment of contact in Figs. 45 3 and 4, when the cam F' is about to be depressed by the wiper-roll w' . In Fig. 5 the cam F' is shown in its position of complete depression. As the wiper-roll w' presses the cam F' down the frame F , of which the cam 50 F' is substantially a part, is pushed down in the case B against the stress of the springs S . The heel g^2 of the rocker G is thus brought into contact with the ledge b and the toe g^3 de-

pressed. The pin g^4 moves downward in the slot f^2 and actuates the bell-crank lever L , which moves the pawl i^1 into the next tooth of the ratchet-wheel d' . When the movement of the cylinder C carries the printing-counter away from the wiper-roll w' , the springs S reassert themselves, and the counter-frame B is lifted to its normal position, the heel g^2 of the rocker G is brought into contact with the upper ledge b^2 , and thus moves the bell-crank L and the connected pawl back to the normal position shown in Fig. 3, there- 60 by advancing the counter one unit or number in preparation for the next printing impact. The counter is so arranged that the printing impact may not disturb the positions of the type-disks. As indicated by the arrows in Figs. 3 and 5, the movement of the counter is such that the tangential component of the printing impact will be exerted against the normal course of advance of the disks and so that the pawls of the counter 70 will resist any tendency to untimely displacement of the type-disks. The same safeguard 75 prevents the inking-rolls from disturbing the disks.

What I claim, and desire to secure by Letters Patent, is—

1. In a printing-counter, the combination of a case, a disk-frame slidingly mounted in the case, disk-advancing mechanism connected with the frame and actuated by its sliding 85 movement, an actuating cam or projection forming part of and projecting from the frame to a height below that of the printing row of characters on the disks substantially as described. 90

2. The combination, with one of the prime members of a printing-press of a printing-counter, consisting of a case, a disk-frame slidingly mounted in the case, and having thereon a disk-actuating cam located below 95 the type-surfaces of the disks, and a wiper, mounted on the press-frame and adapted to make contact with the actuating-cam and depress the frame between printing impacts of the counter, substantially as described. 100

Signed by me at Boston, Massachusetts, this 4th day of March, 1901.

ERNEST FRANK HANSON.
